UNITED STATES PATENT OFFICE.

JESSE OVERTON, OF JACKSON, TENNESSEE.

COMBINED FIRE-PLACE AND COOKING-STOVE.

SPECIFICATION forming part of Letters Patent No. 286,058, dated October 2, 1883.

Application filed April 7, 1883. (No model.)

To all whom it may concern:

Be it known that I, JESSE OVERTON, of Jackson, in the county of Madison and State of Tennessee, have invented certain new and 5 useful Improvements in a Combined Fire-Place and Cooking-Stove; and I do hereby declare the following to be a full, clear, and exact description of the invention, such as will enable others skilled in the art to which it pertains 10 to make and use it, reference being had to the accompanying drawings, which form part of this specification.

My invention relates to an improvement in a combined fire-place and cooking-stove; and 15 it consists in the combination of an open-front fire-place, the grate which is placed therein, and a front which can be applied to the opening in the front of the stove.

The object of my invention is to provide a 20 combined fire-place and stove which is adapted to be used in two rooms at once, the front part serving as a fire-place to heat the room, the back part for cooking in another room.

Figure 1 is a vertical cross-section of my 25 invention complete. Fig. 2 is a front view of the same.

A represents the body of the stove, which 30 will be of any desired shape, and which has an open front or fire-place, B, at the front end. In this fire-place is placed the grate C, which 35 which has a support, D, formed at its rear end, so as to support it at this point, and which is supported upon its front end upon suitable projections, E, which extend outward from the inner side of the stove. This grate 40 inclines from its rear end toward the front, so that it will be deepest at the front, instead of being of an equal depth the full length of the grate-bars. By means of this support, which 45 is secured to its rear end, and the inclined shape which is given to the bars, a self-supporting basket is formed, which can be taken out at any time, even while filled with fire, and transferred to another fire-place in which 50 there is no grate. The front part of the basket will then either be supported by the grate-bars of the basket or can be propped upward any desired distance by placing objects under it.

55 The ends of the basket are made solid, as shown, so that no fire or ashes can fall out at

this point. Under the grate is placed an ash-pan of the usual construction.

At each end of the grate or basket are placed 55 suitable tiles, which serve to protect the iron and prevent it from radiating heat too rapidly at these points, and on the back and bottom of the grate are placed other tiles for a similar purpose. The back and bottom tiles are much heavier than those at the end, as it is necessary to dispense with feet to the stove or grate, and it then becomes necessary to prevent the heat from radiating through the bottom too rapidly, so as to endanger or burn the floor.

An iron hearth, F, is formed upon the front 60 of the frame, and upon this iron hearth is placed the cover G, preferably of the shape shown, and which is provided with a damper, H. This cover is placed over the front of the fire-place when it is desired to regulate the draft. 65 When the damper is opened, the cover acts like a blower. When the damper is closed, all draft is shut off from the fire.

Upon the top of the frame of the stove is 70 formed the flange I, which serves to form a joint with a mantel-piece or partition or wall through which the stove is placed.

In that part of the stove which is to extend 75 in the kitchen will be formed an oven of any desired shape or construction, and which may 80 be heated either from above or from both above and below, as may be preferred.

In order to prevent the heat from radiating 85 through the bottom of the stove too rapidly, an air-flue, J, is made through the bottom part, and this flue is controlled at its front by means of the damper L. The air from this flue rises up back of the partition N and passes up through the stove-pipe with the products of combustion. This damper also serves to 90 regulate the draft of the stove. Upon the upper portion of the frame, just over the fire-place, are also formed holes, upon which the cooking-utensils can be placed.

This stove is especially designed for small 95 houses, where it is designed to economize fuel. The stove is made then to heat both rooms, and to serve for cooking purposes at the same time.

Having thus described my invention, I now claim—

1. The combination of a stove provided with

an open-front fire-place and an oven, and which is adapted to be passed through the wall, so as to have its ends in opposite rooms, in combination with the cover G, provided with suitable registers, which cover is made to close the whole front portion of the stove, substantially as shown.

2. A stove having an open front at one end, a flange upon its top to form a tight joint with the partition, and having the oven and the

rear portion of the stove to extend into another room on the other side of the partition, substantially as specified.

In testimony whereof I affix my signature in presence of two witnesses.
